INVENTOR
ROBERT HUNTER CAMPBELL
BY HIS ATTORNEYS
Howson and Howson

UNITED STATES PATENT OFFICE.

ROBERT HUNTER CAMPBELL, OF UPPER EDMONTON, LONDON, ENGLAND, ASSIGNOR
TO SPARKLETS LIMITED, OF LONDON, ENGLAND.

INFLATING APPARATUS FOR LIFE-SAVING DEVICES.

Application filed October 22, 1925, Serial No. 64,190, and in Great Britain August 5, 1925.

This invention relates to capsules, or containers, for gases, or liquids, under pressure (hereinafter referred to as the capsule) and is more especially applicable to capsules of 5 the kind described in the specification of my patent in the United States of America No. 1,387,451, and this invention has for its object to provide means whereby the said capsule is adapted for use in inflating apparatus for saving life from drowning, or for 10 other purposes, and mainly consists in providing the said capsule with a closure and a fitting for breaking the said closure at a weak part whereby the contents of the capsule can be quickly liberated therefrom and allowed to flow into and inflate a flexible bag, or container.

According to this invention the closure of 20 the capsule is provided with a stem-like portion of any suitable length which projects outwardly from the capsule, and this portion is made hollow for a part of its length and is externally screw-threaded or otherwise 25 grooved, so that it can be screwed, or otherwise secured, into a piece projecting into the interior of the flexible bag, or container, to be inflated. The said piece into which the projecting portion of the closure is screwed 30 may be secured to, or formed in one with, a handle secured into an opening in the said bag or container.

I will more particularly describe this invention with reference to the accompanying drawing in which Figure 1 shews in section 35 so much of the upper part of a capsule as is necessary to shew the application thereto of a closure in accordance with this invention. Figure 2 shews, partly in section, and drawn to a smaller scale than Figure 1, the closure of the capsule screwed into a handle 10 of a flexible bag, or container, to be inflated and Figure 3 is a similar view to Figure 2 shewing the closure broken.

The capsule 1 is closed, in the example 15 shewn in Figure 1, by a closure 2, preferably of soft metal, screwed into an internally screw-threaded recess 3 formed in the open end of the said capsule. The closure 2 is provided with an outwardly projecting 20 stem-like portion 4 hollowed at 5 so that it can be easily broken, and externally screw-threaded so that it can be screwed into a piece 6 which, as shewn in Figure 2, may constitute both the lower part of a handle

7 of a flexible bag, or container, 8 to be inflated, and a closure to an opening 9 of the said bag, or container, through which the capsule 1 is passed. The piece 6 of the handle 7 is screwed into a flanged socket 10 secured in the opening 9 of the bag, or container, 8 by a lock nut 11 which, through the interposition of washers 12 and 13 of suitable material clamp the edge of the material in which the said opening is formed between the flange of the said socket and the said 65 lock nut.

When it is required to release the gases, or liquids, in the capsule 1 the operator holds the handle 7 in one hand and grips, through the flexible bag, or container, 8 the said capsule with his other hand and by a sharp angular movement breaks the projecting portion 4 of the closure 2 of the said capsule, as shewn in Figure 3, thereby liberating the gas which then flows into and inflates the said bag, or container.

When desired the handle 7 can be removed, the empty capsule 1 extracted through the opening 9 and after removing the broken stem-like portion 4 of the closure 2 from the piece 6 of the handle 7 another closed and charged capsule can be screwed into the said piece and the handle be again screwed into the socket 10 in readiness for inflating the bag, or container, when desired.

The portion of the broken closure 2 remaining in the used capsule 1 can be descrewed, or otherwise removed therefrom, as described in my aforesaid specification and the said capsule may then be refilled and be closed by a new closure ready for re-use.

What I claim is:

1. In apparatus of the type described, a flexible bag having an opening, a capsule within said bag, a closure for the bag opening, and a handle formed in one with said closure, in combination with a stem-like portion made hollow and breakable for part of its length, secured into said capsule and said closure, relative angular displacement of 95 said capsule and said handle being adapted to break said stem-like portion and to discharge the capsule contents into the bag.

2. In apparatus of the type described, a flexible bag having an opening, a capsule 105 within said bag, a flanged socket fitted into said bag at said opening, a closure formed to fit snugly into said flanged socket, and a

handle formed in one with said closure, in combination with a stem-like portion made hollow and breakable for part of its length, secured into said capsule and said closure, 5 said flanged socket having an opening through which said capsule may be removed from the bag, and relative angular displacement of said capsule and said handle being adapted to break said stem-like portion and to discharge the capsule contents into the bag.

In testimony whereof I have signed my name to this specification.

ROBERT HUNTER CAMPBELL.
